US00D876164S

(12) **United States Design Patent** (10) Patent No.: **US D876,164 S**
(45) Date of Patent: **** Feb. 25, 2020**

(54) **FLOW-THROUGH AGITATOR**

(71) Applicant: **Runway Blue, LLC**, Alpine, UT (US)

(72) Inventors: **Kim L. Sorensen**, Alpine, UT (US);
Steven M. Sorensen, Alpine, UT (US);
David O. Meyers, East Layton, UT
(US); **Douglas B. Espenschied**, Lehi,
UT (US)

(73) Assignee: **Runway Blue, LLC**, Alpine, UT (US)

(**) Term: **15 Years**

(21) Appl. No.: **29/705,308**

(22) Filed: **Sep. 11, 2019**

CLAIM

The ornamental design for a flow-through agitator, as shown and described.

DESCRIPTION

FIG. 1 is a top front perspective view of a flow-through agitator showing the claimed design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is a top front perspective view of another flow-through agitator showing the claimed design;
FIG. 9 is a front view thereof;
FIG. 10 is a rear view thereof;
FIG. 11 is a left side view thereof;
FIG. 12 is a right side view thereof;
FIG. 13 is a top view thereof; and,
FIG. 14 is a bottom view thereof.
